UNITED STATES PATENT OFFICE

KEMPTON ADAMS, OF REDDING RIDGE, CONNECTICUT

MIXER

Application filed April 12, 1928, Serial No. 269,406. Renewed September 6, 1929.

This invention relates to new and useful improvements in mixers.

Its object is to provide a simple and efficient apparatus for mixing different materials, such as the ingredients of concrete.

The modern tendency in concrete practice is to use a stiff mix, and the result is that the mixers now available are not well suited to present requirements. With former apparatus the thorough intermingling of the ingredients of a comparatively dry concrete is a slow and tedious process. It has been found that better results can be obtained by manually working the materials together.

One of the specific objects of the present invention is to provide a power driven machine in which the ingredients are stirred and worked thoroughly and rapidly in the desired consistency.

Another object is to provide an arrangement for quickly and positively discharging the mixed materials from the apparatus.

These and other objects of the invention will appear in the following specification.

In the drawings, Fig. 1 is an elevation, partly in section, of a machine which embodies this invention;

Fig. 2 is a plan view of the same apparatus; and

Fig. 3 is a fragmentary sectional elevation of one of the parts of the apparatus shown in the preceding figures.

This apparatus comprises a supporting frame having an annular horizontal portion 10 in which are supported a series of rollers 11 mounted to turn freely about horizontal axes, and another series of rollers 12 which turn about vertical axes.

20 is a frusto-conical shell having near its upper end a rim 21. This rim is constructed to form a smooth track 22 which rests upon the rollers 11 and a flange 23 which bears against the rollers 12. In it are mounted two series of rollers 24 and 25, the purpose of which will appear later. 26 is a gear member on the shell 20 by means of which the shell and its connected parts are rotated.

To the lower end of the shell 20 is affixed a bottom ring 30 which carries a pivoted closure plate 31 which is held in closed

position by a bolt 32. This member comprises a central post 33 connected to the ring by spider arms 34. On the post 33 are propeller blades 35 which are disposed and constructed to form an interrupted double 55 thread screw of high pitch.

40 is a ring which rests on rollers 24 and bears against rollers 25. To it is affixed a ring gear 41 and an annular member 42. Affixed to the latter are arms 43 which extend 60 down into the shell 20 and are parallel therewith. These arms are triangular in cross section, as shown at 44 in Fig. 2, and their lower ends are affixed to a ring 45. On these arms are vanes 46 which are angularly disposed as 65 shown. The lower ends 47 of these vanes are curved to form scrapers and their upper portions are twisted as at 48. The vanes nearer the bottom of the cone are shorter than those farther up.

The machine is driven from a power shaft 50, keyed to which are gears 51 and 52 which are longitudinally slidable together by means of a bell crank lever 53. 54 is a countershaft which is connected to drive shell 20 in one 75 direction through bevel gears 55 and a gear 56 which meshes with the annular gear member 26, and to drive the member 42 and its arms 43 in the opposite direction through gear 57 which is in mesh with the ring gear 80 41. When gear 51 is in the position shown in Fig. 1, it drives the gear 58 on the counter-shaft 54. Gear 52 can be moved down to engage gears 59 to drive the countershaft in the opposite direction.

The operation of this apparatus will now be described.

Desired materials are put into the shell 20 and the latter with its post 33 and the blades 35 is rotated in an anti-clockwise direction. 90 The blades passing through the mass within the shell tend to raise it and throw it outwardly toward the inner moving surface of the shell. The material obviously will run down and will be rotated to some extent by its contact with the shell. At the same time the arms 43 are rotating in the opposite direction. The forward edges of these arms and the forward ends 47 of the vanes 46 scrape the material from the surface of the 95 100 shell.

shell and as these vanes move through the mass they move it inwardly and upwardly and at the same time turn it over. Thus the materials are most thoroughly agitated and stirred and become completely intermixed in a very short time.

A great advantage of this apparatus is that even with such materials as those of a comparatively stiff concrete mix, it can be run at much higher speeds than are effective with former machines.

Now when the mixing operation is completed, the closure plate 31 is released and swung back into the position in which it is shown at 31A in Fig. 1 and held there by a latch 36. The mechanism is now reversed by means of a lever 53. The blades 35 and the vanes 46 will now drive the mixed materials downwardly so that it will be discharged more rapidly and more completely than if it were permitted to drop out by the action of gravity alone.

The apparatus described is shown more or less diagrammatically and is intended only to illustrate the principle disclosed herein, as many modifications of structure are possible without departing from the spirit and scope of the invention as defined in the following claims.

30. What I claim is:

1. A mixer comprising a receptacle arranged to be rotated about a substantially vertical axis, means therein for moving material upwardly and outwardly, and other means therein for moving material inwardly and turning it over.

2. A mixer comprising a receptacle arranged to be rotated about a substantially vertical axis, a removable bottom therefor, a plurality of propeller blades within the receptacle and rotatable therewith for moving material, and means for reversing the direction of rotation of the receptacle and the blades.

45. 3. A mixer comprising a receptacle arranged to be rotated about a substantially vertical axis, a removable bottom therefor, a plurality of propeller blades within the receptacle and rotatable therewith for moving material, a plurality of vanes arranged to be rotated around said blades in the opposite direction, and means for reversing the direction of rotation of the receptacle and the blades and of said vanes.

50. 4. A mixer comprising a frusto-conical shell arranged to be rotated about a substantially vertical axis, and means disposed centrally thereof and supported from above for moving material upwardly and outwardly.

60. 5. A mixer comprising a frusto-conical shell arranged to be rotated about a substantially vertical axis and having an upwardly and outwardly tapered material supporting surface, means disposed centrally thereof

for moving material upwardly and outwardly, and other means near the inner surface of the shell for moving material inwardly.

6. A mixer comprising a frusto-conical shell arranged to be rotated about a substantially vertical axis, means disposed centrally thereof for moving material upwardly and outwardly, and other means near the inner surface of the shell for moving material inwardly and turning it over.

7. A mixer comprising a frusto-conical shell arranged to be rotated about a substantially vertical axis, means disposed centrally thereof and rotatable therewith for moving material upwardly and outwardly, and other means near the inner surface of the shell and rotatable in the opposite direction for moving material inwardly.

8. A mixer comprising a frusto-conical shell arranged to be rotated about a substantially vertical axis, and a plurality of vanes rotatable in the opposite direction near the inner surface of said shell.

9. A mixer comprising a frusto-conical shell arranged to be rotated about a substantially vertical axis, and a plurality of twisted vanes rotatable in the opposite direction near the inner surface of said shell, said vanes being arranged to lift the material and turn it over.

10. A mixer comprising a frusto-conical shell arranged to be rotated about a substantially vertical axis, means disposed centrally thereof for moving material upwardly and outwardly, and a stirring mechanism rotatable in the opposite direction near the inner surface of said shell arranged to move material upwardly and inwardly and to turn it over.

11. A mixer comprising a frusto-conical shell arranged to be rotated about a substantially vertical axis, a removable bottom therefor, a plurality of propeller blades disposed centrally within the shell and rotatable therewith for moving material upwardly and outwardly, and a stirring mechanism rotatable in the opposite direction near the inner surface of said shell arranged to lift the material and turn it over.

12. A mixer comprising a frusto-conical shell arranged to be rotated about a substantially vertical axis, a removable bottom therefor, a plurality of spaced propeller blades disposed centrally within the shell and rotatable therewith for moving material upwardly and outwardly, and a stirring mechanism comprising a plurality of spaced twisted vanes rotatable in the opposite direction near the inner surface of said shell arranged to lift the material and turn it over.

13. A mixer comprising a frusto-conical shell arranged to be rotated about a substantially vertical axis, a removable bottom therefor, a plurality of spaced propeller blades disposed centrally within the shell and rotat-

able therewith for moving material upwardly and outwardly, a stirring mechanism comprising a plurality of spaced twisted vanes rotatable in the opposite direction near the inner surface of said shell arranged to lift the material and turn it over, and means for reversing the directions of rotation of the shell and propeller blades and of said stirring mechanism.

14. A mixer comprising a receptacle, means therein for moving material upwardly and outwardly, and positively actuated means movable independently of said first named means for moving material inwardly and turning it over.

15. A mixer comprising a receptacle, means therein for moving material upwardly and outwardly, and positively actuated twisted means movable independently of said first named means for moving material inwardly and turning it over.

16. A mixer comprising a receptacle, means disposed centrally therein for moving material upwardly and outwardly, and other means within the receptacle for moving the material inwardly and turning it over.

17. A mixer comprising a receptacle, means disposed centrally therein for moving material upwardly and outwardly, and other means within the receptacle and disposed near the inner surface thereof for moving the material inwardly and turning it over.

18. A mixer comprising a frusto-conical shell, rotatable means disposed centrally thereof for moving material upwardly and outwardly, and a stirring mechanism rotatable in the opposite direction near the inner surface of said shell arranged to move material upwardly and inwardly and turn it over.

In witness whereof, I have hereunto set my hand this 10th day of April, 1928.

KEMPTON ADAMS.
